PASSOVER SEDER PLATE

Daniel J. Frucher, Lawrence, N.Y., assignor to Educational and Recreational Associates Ltd., New York, N.Y.

Filed Mar. 3, 1975, Ser. No. 554,749

Term of patent 14 years

Int. Cl. D7—01

U.S. Cl. D7—26

FIG.1

FIG.2

FIG.3

FIG. 1 is a front view of a passover Seder plate showing my new design;

FIG. 2 is a side elevation view thereof, the opposite side being substantially identical with the view shown; and

FIG. 3 is a cross-sectional view taken on line 3—3 of FIG. 1.

I claim:

The ornamental design for a passover Seder plate, as shown and described.
